[57]

ABSTRACT

A unit for storing and serving articles, such as condiments, from containers, which is adaptable for countertop installation. The unit includes a containment section having an upper open end and having a first support post disposed therein. A movable second support post is telescopically connected to the first support post, and has an uppermost position wherein a portion extends above the open end of the containment sections and a lowermost position wherein substantially all of the second support post is within the containment section. Collar-like and bushing-like sections are connected to the posts to serve as means for maintaining the second support post in either the uppermost position or in the lowermost position thereof. Container holding means is connected to the second support post for holding containers in position. When the articles are to be stored, the second support post is lowered into its lowermost position which lowers the containers containing the articles within the containment section. When the articles are to be served, the second support post is telescoped to its uppermost position and latched in position. Thus, the containers are accessible to the server.

**UNIT FOR STORING AND SERVING ARTICLES SUCH AS
CONDIMENTS**

The present invention relates to a unit for storing and serving articles such as condiments. The unit is particularly adaptable for use in placement into countertops, movable carts, bars, and other types of serving counters where there is the frequent handling and serving of foods or beverages requiring the use of condiments or the like.

One of the major industries having use for such a unit is the transportation industry, and particularly the airline branch of that industry, where the serving of foods and beverages is carried on in relatively short periods of time and within relatively confined areas, and condiments are required as a supplement to these foods and beverages. In the past, it has been particularly difficult to handle the serving of condiments in a moving airline because of the narrow aisles and the motions of the plane itself. The serving of foods and beverages usually requires the use of condiments and generally requires the server to use two hands. Consequently, it is desirable to have the condiments in an accessible location and in one which does not take up much room if the server is using a movable cart. It is also desirable to provide a place where the condiments can be stored readily.

It is therefore an object of this invention to provide for a unit for storing and serving articles, such as condiments.

More particularly, it is an object of this invention to provide for a unit for serving articles from a plurality of containers which may be readily stored away and which may be installed into a countertop or into the top of a movable cart.

It is another object of this invention to provide for such a unit that will prevent the entrance or spillage of food particles into the hollow areas of the unit.

In one of its many broad aspects, the present invention provides for a unit for storing and serving articles from containers which comprises in combination: a hollow containment section having an upper open end; a first support post within said containment section and disposed perpendicularly to said open end; a movable second support post telescopically connected to said first support post, said second support post having an uppermost position wherein a portion thereof extends above the open end of said containment section and having a lowermost position wherein a substantial portion of said second support post is within said containment section; means connected to said support posts for maintaining said second support post in the uppermost position thereof; means connected to said support posts for maintaining said second support post in the lowermost position thereof; and, container holding means connected to the second support post for holding the containers in position, said container holding means being sized to fit within said containment section when the second support post is in the lowermost position thereof.

In utilizing this unit, a suitable size opening will generally be provided in a counter or cart top for insertion of the containment section therein. The upper open end of the containment section will then be approximately flush with the countertop. Preferably, the first support post is of a tubular form and the second support post is of a tubular form coaxially disposed around and spaced from the first support post to form an annular space therebetween. Bushing-like and collar-like sections are provided within the annular space to support and guide the second support post about the first support post. These sections also establish the means for maintaining the second support post in the lowermost and uppermost positions.

The container holding means usually will comprise a plurality of spaced apart sections connected to the second support post, each of these sections having an opening sized to support the containers which will hold the articles. Preferably, these sections will be rotatably connected to the second support post and will have a means adjacent to the second support post for temporarily locking the sections to prevent their indiscriminate rotation about the post. A spring means may be provided in conjunction with the support posts to aid in lifting the

second support post from its lowermost position and to maintain the second support post in both its lowermost and uppermost positions.

Reference to the accompanying drawing and the following description thereof will serve to point out and more fully illustrate the design and construction of this invention as well as to assist in further pointing out advantageous features in connection therewith.

FIG. 1 is a partial elevational view of a preferred embodiment of this present invention.

FIG. 2 is a plan view of the embodiment of FIG. 1.

FIG. 3 is a full longitudinal section of the embodiment of FIGS. 1 and 2 as taken along section line 3-3 of FIG. 2.

FIG. 4 is a cross-sectional view of the embodiments of FIGS. 1 and 2 as taken along section line 4-4 of FIG. 1.

FIG. 5 is a partial longitudinal sectional view of the second support post showing the bushing-like sections.

FIG. 6 is a cross-sectional view of the second support post as taken along section line 6-6 of FIG. 5.

FIG. 7 is a cross-sectional view of the second support post as taken along section line 7-7 of FIG. 5.

FIG. 8 is a partial longitudinal sectional view of the first support post showing the collar-like sections.

FIG. 9 is a cross-sectional view of the first support post as taken along section line 9-9 of FIG. 8.

FIG. 10 is a cross-sectional view of the first support post as taken along section line 10-10 of FIG. 8.

FIG. 11 is a plan view of the handle cover of the second support post.

FIG. 12 is an elevational view of the handle cover of FIG.

11.

FIG. 13 is a plan view of the second support post.

FIG. 14 is a partial elevational view of the second support of FIG. 13.

FIG. 15 is a longitudinal section of the embodiment of FIGS. 1 and 2 showing the lowermost position of the second support post.

FIG. 16 is a modification of the collar-like and bushing-like sections that may be used in conjunction with the present invention.

Referring now more particularly to FIGS. 1, 2, and 3 of the drawing, there is shown the storing and serving unit of this present invention. The unit includes a hollow containment section 3 which may be inserted into an opening 27 of a countertop or cart top 26. The containment section 3 has an open end 28 which has a lip portion 25 adapted to rest and be supported on the countertop 26. Within the section 3 there is disposed a first support post 1 which is anchored to a lower stabilizer section 4 via fastener 16 and threaded plug 15. For ease in fabrication and ease in utilization, support post 1 is of a tubular form and preferably circular in cross section. An upper stabilizer section 5 is used to support and stabilize support post 1. A rubber seal 17 is provided around the connection of support post 1 and section 5 to prevent spillage of food particles from entering into the lower portion 9 of the containment well.

A movable second support post 2 is telescopically connected to support post 1. In other words, support post 2 is free to slide vertically around support post 1. Of course, to provide this telescopic connection the cross section of support post 2 should also be circular. Actually, in this preferred embodiment the two support posts are spaced apart to form an annular space 24 therebetween. A bushing or bushing-like section and a collar or collar-like section are provided within this space to aid in guiding and supporting post 2 around the first support post 1.

Support post 2 has an uppermost position, shown in FIGS. 1 and 3, wherein a substantial portion thereof extends above the open end 28 of the containment section 3. Support post 2 has a lowermost position, shown in FIG. 15, wherein a substantial portion of support post 2 is contained within the containment section. The bushing-like and collar-like sections also serve as the means for maintaining support post 2 in these two positions.

Reference is now made to FIGS. 5, 6, 7, 8, 9, and 10 for a detailed illustration of these sections. In FIGS. 5 and 6 the second support post 2 is shown with a bushing-like section 31 connected to the interior wall thereof. Section 31 serves as a latch for maintaining the support post 2 in the uppermost position and in the lowermost position. The inner surface 32 of section 31 will of course contact the outer surface of support post 1 for guiding purposes as shown in FIGS. 3 and 15 of the drawing. In FIGS. 8, 9, and 10 of the drawing there is shown detailed views of support post 1 with two segment-collar-like sections 41 and 40 attached to the outer wall of the post 1. Their outer surfaces 21 and 22 will of course contact the inner surface of support post 2 for guiding purposes as shown in FIGS. 3 and 15 of the drawing. Section 41 serves as a catch or dog and is used in conjunction with section 31 for maintaining support post 2 in the uppermost position thereof. Section 31 has a portion 33 that extends above the segment-collar-like section 41 through the opening 45. Portion 33 in turn has an extension 36 extending circumferentially which overlaps the upper surface 42 of section 41 as support post 2 is rotated when in the uppermost position as shown in FIG. 3. As is seen in FIG. 3, bushing-like section 31 and collar-like section 41 provide a means whereby the second post 2 may be supported in its uppermost position. The particular shape of these sections should not be limiting upon this present invention for others are contemplated. For example, in FIG. 16 a modification of their shape is illustrated. The bushing-like section 31' has a portion 33' that extends above a collar-like section 41' when post 2' is in its uppermost position. Portion 33' in turn has a circumferentially extending extension 36'. Instead of a horizontal surface, extension 36' is notched to have an oblique surface 46. The corresponding segment-collar-like section 41' has a surface 42' shaped to mate with surface 46. This particular shape establishes a locking-type connection when support post 2' is rotated into position around support post 1'.

Referring to FIGS. 9 and 10 again, it is seen that segment-collar-like section 40 is somewhat smaller than section 41. Section 40 is sized to clear the bushing-like section 30 located within support post 2. Section 30 is segmented to bypass section 40 as post 2 is moved vertically and serves only as a guide means. On the other hand, section 31 cooperates with section 40 to maintain support post 2 in its lowermost position. In other words, section 31 has a portion 34 which extends below section 40 when post 2 is in the lowermost position. Portion 34 in turn has a circumferentially extending extension 35 that overlaps a part of the lower surface 43 of section 40 as support post 1 is rotated when in its lowermost position as shown in FIG. 15 of the drawing.

Referring to FIGS. 1, 2, 3, and 4 of the drawing there is shown the container holding means which includes a plurality of spaced apart sections 20 connected to support post 2. Each of these sections has an opening 37 sized to support containers such as open-ended container 70 of FIG. 1. These sections are sized to fit within the containment section 3 when the second support post 2 is in the lowermost position. Preferably, although not necessarily, sections 20 are rotatably connected to support post 2 so that they may be swung into various positions as indicated by the dashed line of FIG. 4. Spacers 10 are provided between the sections 20 for aesthetic purposes as well as a means to support sections 20 about post 2. To prevent the sections from rotating at all times, a plunger 55 or other suitable means is located adjacent tubular member 2 for temporarily locking the sections to prevent their rotation about post 2. The plungers 55 include a ball 56 and a spring 59 biased to force ball 56 against support post 2. Notches 57 are provided in support post 2 so that when a section is rotated and the plunger passes over a notch 57 the ball 56 will be forced into the notch and thus temporarily lock section 20 in a particular location around the support post 2.

A further refinement of this serving and storing unit facilitate the particular arrangement by which it may be lowered or raised. In other words, a compression spring 18 or other suitable spring means is disposed within the support posts 1 and 2 for exerting a force to lift and maintain the

second support post 2 in the uppermost position thereof. Spring 18 is inserted within support posts 1 and 2 and is maintained therein by plug 15 and a handle cover 50. The details of handle cover 50 are illustrated in FIGS. 11 and 12 of the drawing. There the cover 50 is shown with an opening 54 to facilitate grasping the handle. Lower portion 69 of handle 50 is adapted to slide within the opening of support post 2. Projections 51 are disposed around the circumference of portion 69 for the connection to the top of support post 2. In FIGS. 13 and 14 the top portion of support post 2 is illustrated. On the top are located boot-shaped openings 62 which are spaced apart to correspond with the spacing of projections 51 of handle 50. After the spring 18 is inserted within the support posts, the cover handle 50 is slipped into the top of support member 2 so that the projections 51 slide through portions 60 of openings 62. The handle 50 is then rotated so the projections 51 rotate into portions 61 of openings 62. Thereafter they are locked in this position by a set screw 52 which is inserted into the threaded hole 49 of handle 50 and screwed until it is in pressure contact with the end of the support member 2 as shown in FIG. 3.

An O-ring or other suitable sealing means 77 is inserted between the support posts 1 and 2 and a nylon washer 53 is inserted between cover 50 and the upper section 2 to prevent entrance of spillage into the hollow areas of the mechanism. Of course, other refinements may be made without diverting from the scope of the invention. It is to be noted that the specific illustrations shown here are illustrative only and any variations of structure and proportions should be considered to form part of the invention insofar as they fall within the spirit and scope of the claims.

I claim as my invention:

1. A unit for storing and serving articles from containers which comprises in combination:
  - a. a hollow containment section having an upper open end;
  - b. a first longitudinal support post within said containment section and disposed perpendicular to said open end, said first support post being positioned near the periphery of said containment section;
  - c. a movable second support post telescopically connected to said first support post, said second support post having an uppermost position wherein a portion thereof extends above the open end of said containment section and having a lowermost position wherein a substantial portion of said second support post is within said containment section;
  - d. means connected to said support posts for maintaining said second support post in the uppermost position thereof;
  - e. means connected to said support posts for maintaining said second support post in the lowermost position thereof; and,
  - f. container holding means connected to the second support post for holding containers in position, said container holding means being sized to fit within said containment section when the second support post is in the lowermost position, said container holding means including a plurality of spaced apart sections connected to the second support post, each of said spaced apart sections having an opening sized to hold and support said containers, said spaced apart sections being rotatably connected to the second support post.
2. The unit of claim 1 further characterized in that said first support post is of a tubular form and in that said second support post is of a tubular form coaxially disposed around and spaced from said first support post to form an annular space therebetween and in that there is provided bushing and collar sections within the annular space.
3. The unit of claim 1 further characterized in that each of said spaced apart sections has a means adjacent to the second support post for temporarily locking said section to prevent the indiscriminate rotation therearound.

4. The unit of claim 1 further characterized in that a spring means is provided in conjunction with said second support post for exerting a lift force upon said second support post.

5. The unit of claim 2 further characterized in that the means for maintaining said second support post in the uppermost position includes a segment-collar section connected around said first support post within the annular space and a bushing section connected to the interior of the second support post within the annular space, said bushing section having a portion that extends above the segment-collar section when the second support post is in its uppermost position, said portion having an extension that overlaps a part of the upper surface of the segment-collar section as the second support post

is rotated when in the uppermost position thereof.

6. The unit of claim 2 further characterized in that the means for maintaining said second support post in the lowermost position includes a segment-collar-like section connected around said first support post within the annular space and a bushing section connected to the interior of the second support post within the annular space, said bushing section having a portion that extends below the segment-collar section when the second support post is in its lowermost position, said portion having an extension that overlaps a part of the lower surface of the segment-collar section as the second support post is rotated when in the lowermost position thereof.
